UNITED STATES PATENT OFFICE.

VINCENT BENDIX, OF CHICAGO, ILLINOIS.

ENGINE-STARTER.

1,276,862.

Specification of Letters Patent. Patented Aug. 27, 1918.

Application filed April 26, 1915. Serial No. 24,030.

To all whom it may concern:

Be it known that I, VINCENT BENDIX, a citizen of the United States, residing at Chicago, Cook county, Illinois, have invented certain new and useful Improvements in Engine-Starters, of which the following is a specification.

My invention relates to a starter for an engine such as a gas engine and the like and the object thereof is to provide a simple, efficient and reliable device of this character operated by a prime mover of any kind such, for instance, as an electric motor. My starter is of that type characterized by a screw-shaft or the like operated by a prime mover indirectly by gearing from the armature shaft and having mounted thereon a driving member in the form of a pinion adapted to travel longitudinally on the screw-shaft and to be automatically meshed with some member of the engine and to be thereupon driven or rotated for rotating such engine member. Thereafter the pinion is adapted to be automatically demeshed from such engine member when the engine operates on its own power and to travel longitudinally out of the screw-shaft back to its home position. The particular object of this invention is to provide a construction concerned more particularly with the screw-shaft and the gearing with the motor whereby the screw-shaft is capable of a longitudinal movement with respect to such gearing in which the screw shaft is mounted to slide.

In the drawing the figure is a sectional elevation of a structure embodying my invention.

Referring to the particular embodiment of my invention as shown in the drawing the prime mover is here an electric motor 1 whose armature shaft is extended to form the driving shaft 2. To the outer end of this shaft is secured a driving pinion 3 meshing with a gear 4. The motor is preferably mounted in a frame or casing 5 which incloses the starter mechanism or transmission and also provides a bearing 6 for the inner end of the screw-shaft herein-after described.

The screw-shaft 7 is screw-threaded at its intermediate portion, its inner end being cylindrical and having two different diameters, the outermost plain portion 7^a being of the smaller diameter and the innermost plain portion 7^b being of the larger diameter.

This screw shaft has separate and smaller screw-threads 8 at its outer end screwing into a bushing 9 mounted in an outboard bearing 10 of a casing 11 which is secured to the casting 5.

In the broader aspect of my invention this bushing may be considered as part of the screw shaft, providing at that end a plain portion similar to that at the other end thereof, these two end plain portions being 60 journalized in the bearings 10 and 16.

A pinion 12 which constitutes the driving member of the starter mechanism is screw-threaded upon the intermediate screw-threaded portion of the shaft 7 and is adapted to engage a rotatable member connected with the engine to be started. In the present instance such rotatable member is a circular rack 13 secured to or forming a part 75 of the fly-wheel 14 of the engine.

The screw shaft has a yielding driving connection with the driving gear 4 and it is also mounted therein as to be capable of a slight longitudinal movement for a purpose hereinafter explained. The innermost 80 cylindrical section 7^a of the screw-shaft passes centrally through the driving gear 4 which is mounted to slightly oscillate thereon and through which the screw-shaft is adapted to slide longitudinally to a slight 85 extent. The outermost end of this portion or section 7^a of the screw shaft is supported by and arranged to slide in the bearing 6. This movement is limited by contact between the larger portion or section 7^b with the 90 gear 4 or by the extreme inner end of the screw-shaft with the end of the bearing 6.

The yielding driving connection between the gear 4 and the screw-shaft consists of a spring 15 coiled around the larger portion or section 7^b and secured or anchored at its ends to the gear and screw-shaft respectively. The inner end of the spring is provided with a loop or eye 16 which engages a pin 17 projecting laterally from the outer side 100 of the gear 4. The other end of the spring terminates in a loop or eye 18 which is anchored to a stud 19 screwing into the screw-shaft. It will be understood that the motion of the prime mover is transmitted from 105 the armature shaft 2 to the screw shaft through the pinion 3, gear 4, pin 17, spring 15 and stud 19.

Describing the mode of operation and beginning with the pinion 12 in its inward 110

- or left-hand position on the screw shaft instead of its position of mesh with the fly-wheel, as shown in the drawing, and assuming that the electric motor has just been started, the screw-shaft is rotated through the driving connections just described. The pinion 12 will thereupon be advanced to the right longitudinally of the screw shaft and will mesh with the fly wheel 14. When 5 the pinion is in full mesh and its longitudinal movement has been arrested by the thrust collar 9^a forming a part of the bushing 9 it will be rotated by the screw shaft and consequently the engine will be rotated. 10 When the engine begins to run on its own power and the fly wheel 14 is thereupon rotated at an increased speed, the pinion 12 will be automatically demeshed by being moved to the left longitudinally of the screw- 15 shaft. After moving a slight distance away from the fly wheel after such demeshing, the pinion will momentarily stop in its longitudinal movement and will rotate with the screw shaft. When the screw shaft has 20 slowed down somewhat the pinion will thereupon move longitudinally back to its home position.

In the event that in the longitudinally advanced movement of the pinion 12, its 30 teeth should not register with the teeth of the fly wheel, the screw-shaft is capable of yielding slightly toward the left in the manner above explained. Owing to this arresting of the pinion which is thereby cushioned 35 by the yielding movement of the shaft, such pinion will start to turn and thereupon the teeth will be brought into register and a complete and proper meshing thereupon assured. This yielding of the screw-shaft 40 cushions the contact between the pinion and the engine member and prevents shock or jar of contact between said parts.

The yielding driving connection possesses the practical advantage of compensating for 45 the variable engine speed caused by the operation of the engine at the compression points and consequently any possible vibration of the pinion 12 on the screw shaft due to this variation in speed is cushioned and 50 rendered immaterial in practice if any such vibration takes place at all, besides which the starting shock is cushioned.

I claim:

1. A starter for engines comprising a shaft 55 having an intermediate screw-threaded portion, a driving device which is screw-threaded upon the shaft and adapted to travel longitudinally thereon and to engage a part of the engine to be driven, a driving gear which 60 is mounted on the screw-shaft and in which the latter is adapted to slide, and a yielding driving connection between said gear and the shaft.
2. A starter for engines comprising a shaft 65 having an intermediate screw-threaded por-

tion and mounted for endwise movement, a driving device which is screw-threaded upon the shaft and adapted to travel longitudinally thereon and to engage a part of the engine to be driven, a driving gear which is loosely 70 mounted on the screw shaft to permit of the latter's endwise movement, and a yielding driving connection between said gear and the shaft.

3. A starter for engines comprising a shaft 75 having an intermediate screw-threaded portion, a driving device which is screw-threaded upon the shaft and adapted to travel longitudinally thereon and to engage a part of the engine to be driven, a driving gear which 80 is loosely mounted on the screw-shaft, a projection on one side of the gear, a projection on the shaft and a spring coiled around the shaft and having its ends anchored to said projections.

4. A starter for engines comprising a shaft having an intermediate screw-threaded portion, a driving device which is screw-threaded upon the shaft and adapted to travel longitudinally thereon and to engage a part of the engine to be driven, a driving gear which is mounted on the screw-shaft and in which the latter is adapted to slide, a casing having a bearing which supports one 90 end of the shaft and in which the latter is adapted to slide, and a yielding driving connection between said gear and the shaft.

5. A starter for engines comprising a shaft having an intermediate screw-threaded portion, a driving device which is screw-threaded upon the shaft and adapted to travel longitudinally thereon and to engage a part of the engine to be driven, said shaft having at one end two cylindrical portions of different diameters, the outermost being the smaller, 100 a driving gear which is mounted on such outermost portion and in which the latter is adapted to slide, and a yielding driving connection between said gear and the shaft.

6. A starter for engines comprising a shaft 110 having an intermediate screw-threaded portion, a driving device which is screw-threaded upon the shaft and adapted to travel longitudinally thereon and to engage a part of the engine to be driven, said shaft having at one end two cylindrical portions of different diameters, the outermost being the smaller, a driving gear which is mounted on such outermost portion and in which the latter is adapted to slide, and a yielding driving connection 115 between said gear and the shaft.

7. A starter for engines comprising a shaft having an intermediate screw-threaded portion, a driving device which is screw-threaded upon the shaft and adapted to travel longitudinally thereon and to engage a part 120

- of the engine to be driven, said shaft having at one end two cylindrical portions of different diameters, the outermost being the smaller, a driving gear which is mounted on 5 such outermost portion and in which the latter is adapted to slide, and a yielding driving connection between said gear and the shaft, comprising a spring coiled around the cylindrical portion of the larger diameter,
- 10 a projection on one face of the gear, and a stud on the shaft, the ends of the spring being anchored to the projection and stud respectively.
8. A starter for engines comprising a shaft 15 having plain bearing ends and an intermediate screw-threaded portion, a driving member screw-threaded upon such threaded portion, a gear mounted on the plain portion of the shaft, and a yielding driving connection 20 between said gear and shaft.
9. A starter for engines comprising a shaft having plain bearing ends and an intermediate screw-threaded portion, a driving member screw-threaded upon such threaded portion, an electric motor, a driving pinion on the armature shaft thereof, a gear meshing with said pinion and mounted on a plain portion of the shaft, and a yielding driving connection between said gear and shaft.
- 25 10. A starter for engines comprising a shaft mounted at its ends for longitudinal and rotary movement and having plain portions and an intermediate screw-threaded portion, a driving member screw-threaded 30 upon such threaded portion, a gear loosely mounted on a plain portion of the shaft, and means for transmitting the power of the gear to the shaft.
11. A starter for engines comprising a 35 shaft mounted at its ends for longitudinal and rotary movement and having plain portions and an intermediate screw-threaded portion, a driving member screw-threaded upon such threaded portion, a gear loosely 40 mounted on a plain portion of the shaft, and a yielding driving connection between the gear and shaft.
12. A starter for engines comprising a 45 shaft mounted at its ends for longitudinal and rotary movement and having plain portions and an intermediate screw-threaded portion, a driving member screw-threaded upon such threaded portion, a gear loosely 50 mounted on a plain portion of the shaft, and a yielding driving connection between the gear and shaft,
- 55 a spring driving connection between the gear and shaft.
13. A starter for engines comprising a shaft having a screw-threaded portion and a plain portion, a driving member screw-threaded upon said threaded portion, a gear 60 loosely mounted on said plain portion, and a resilient driving connection operatively connecting the shaft and gear.
14. A starter for engines comprising a shaft having a screw-threaded portion and a plain portion, a driving member screw-threaded upon said threaded portion, a gear 65 loosely mounted on said plain portion, and a driving connection encircling the shaft and operatively connecting the shaft and gear. 70
15. A starter for engines comprising a shaft having a screw-threaded portion and a plain portion, a driving member screw-threaded upon said threaded portion, a gear loosely mounted on said plain portion, and a spring forming a driving connection 75 between the shaft and gear.
16. A starter for engines comprising a shaft having a screw-threaded portion and a plain portion, a driving member screw-threaded upon said threaded portion, a gear 80 loosely mounted on said plain portion, and a yielding driving connection located in the line of power transmission between the gear and the pinion.
- 85 17. A starter for engines comprising a shaft having a screw-threaded portion and a plain portion, a driving member screw-threaded upon said threaded portion, a gear loosely mounted on said plain portion, and a driving connection operatively connecting the shaft and gear, the shaft being mounted for longitudinal sliding movement through the gear.
- 90 18. A starter for engines comprising a shaft having plain bearing ends and an intermediate screw-threaded portion, a driving member screw-threaded upon such threaded portion, a gear mounted on the plain portion of the shaft, and a yielding driving connection 95 between said gear and shaft, the shaft being mounted for longitudinal sliding movement through the gear.
- 100
